(57) CLAIM

I claim the ornamental design for a light support bracket, as shown and described.

DESCRIPTION

FIG. 1 is a front top and left side perspective view of a light support bracket showing my new design.

FIG. 2 is a top view thereof;

FIG. 3 is a bottom view thereof;

FIG. 4 is a right side view thereof, it being understood that a left side view is a mirror image thereof;

FIG. 5 is a front view thereof; and,

FIG. 6 is a rear view thereof.

1 Claim, 2 Drawing SheetsFIG. 1

FIG. 2

FIG. 3

FIG. 4

FIG. 5

FIG. 6
